(57) CLAIM

The ornamental design for a detachable jewelry setting, as shown and described.

DESCRIPTION

FIG. 1 is a front perspective view of the detachable jewelry setting of the instant invention;

FIG. 2 is a front view thereof;

FIG. 3 is a top side view thereof;

FIG. 4 is a bottom side view thereof;

FIG. 5 is a left side view thereof;

FIG. 6 is a right side view thereof;

FIG. 7 is a front perspective environmental view thereof;

FIG. 8 is a front perspective view thereof shown in another environment;

FIG. 9 is a front perspective view thereof shown in another environment;

FIG. 10 is a front perspective view thereof shown in another environment; and,

FIG. 11 is a front perspective view thereof shown in another environment.

The portions of the figures illustrated in broken lines represent unclaimed portions of the detachable jewelry setting and environment and form no part of the claimed design.
